INDEX FRAME ARRANGEMENT

James H. Rand, North Falmouth, Mass., assignor
to Philrand, Inc., North Falmouth, Mass., a
corporation of Massachusetts

Application August 22, 1934, Serial No. 740,953

10 Claims. (Cl. 129—34)

This invention relates to improved index arrangements and particularly to index frame assemblies, such as frames affording panels including sheet metal backing members and a plurality of index strips or the like mounted thereon. In accordance with this invention, such a frame or panel may be provided with means to receive a covering or sheet of transparent resilient material such as celluloid. This sheet may substantially cover the face of the panel to protect the individual index strips and to aid in retaining them in place while permitting them to be readily visible. Thus, a panel of this character is particularly adapted for use under adverse conditions as in a factory, workshop or the like. If the outer face of the transparent protective sheet should become soiled, it may be readily cleansed.

A further aspect of this invention relates to the arrangement of the marginal portions of the index frame, not only to afford channels to receive the edges or ends of the index slips, but also to afford reinforcing beads which may engage and protect the edges of a transparent covering strip. Panels of this character may normally be handled as separate units or, if desired, may be assembled in sets supported by larger or master frames or book-like containers, for example, containers of the character disclosed in my copending application No. 740,954, filed on even date herewith which are characterized by channels to receive the ends of index elements. For this purpose, the extremity of the panel forming the subject matter of this invention may be provided with flanges projecting beyond its own marginal channels to engage the channels of a master frame of the book type.

35 In the accompanying drawing:

Fig. 1 is a broken elevational view of a frame of the book type on which my improved index frames are mounted;

40 Figs. 2 and 3 are sections on lines 2—2 and 3—3, respectively, of Fig. 1;

Fig. 4 is a broken front elevation of an optional type of frame; and

45 Figs. 5 and 6 are sections on lines 5—5 and 6—6, respectively, of Fig. 4.

In the accompanying drawing, the numeral 1 designates one leaf of a master index frame which may be of the book type and is provided with beaded edge portions 2 extended to provide flanges 3 which cooperate with the body portion of the leaf in defining marginal channels to receive index material. One margin of each leaf may be connected to an adjoining leaf by a hinge 4. A frame of this type is more completely disclosed in my copending application No. 740,954. Disposed

on the leaf 1 and held in place by the flanges 3 are smaller frames or index panels 10 arranged in accordance with the present invention. Each of the smaller panels may comprise a body portion or backing member of sheet metal, the extremities of which afford flanges 11 engageable within the channels afforded by flanges 3. Between these flanges or extensions 11 the margins of the sheet metal member are bent inwardly substantially parallel to its body portion to afford retaining flanges 14. The flanges 14 terminate in spaced relation to the end flanges 11 and adjoining each end of the flanges 14, ears or tabs 15 may be arranged substantially in the plane of the flanges 14 but spaced therefrom by slots 16.

5 Index strips 19 may be arranged upon the panel 10 with their ends received in the channels afforded by flanges 14. A transparent covering sheet 20 may then be applied to the panel or frame 10. This cover sheet has each end portion folded 10 to provide a flat, enclosing loop 21 or at least is 20 bent so that its extremity may hook over the ears 15 at an end of the panel 10. A reinforcing or identifying strip 17 which may be formed of cardboard may be disposed within the flattened loop 25 21 with its ends adjoining the ears 15.

The resiliency of the sheet material from which the cover 20 is made permits its ready bowing away from the panel midway between ears 15 at 30 one end of the panel, the strip 17 also being readily distortable thus to permit removal of one or both ends of the sheet from the panel as may be desired.

The master frame 1 may be provided with ears 15 at the ends of its retaining flanges 3 similar to the ears 15 employed on the smaller frame 10. A flattened generally tubular element 116 of sheet material such as light sheet metal or celluloid may have its extremities in interfitting relation with the ears 115. If desired, this flattened tube may receive a reinforcing or identifying strip of cardboard or the like 117. Ordinarily the flattened tube 116 will occupy the position illustrated in Fig. 1, thus forming a retainer at the upper and lower ends of the flanges 3 to prevent accidental removal of the smaller frames 10. When it is desired to remove or replace a frame 10, the member 116 with its reinforcement 117 may be distorted and bowed outwardly so that its ends are removed from engagement with ears 115. Thereupon, the frames 10 may be slid vertically out of engagement with flanges 3.

50 The type of frame illustrated in Figs. 4 and 5 is in general similar to that already described with the exception that the extensions 11 are 55

omitted, the cover sheet 20^a corresponding to the sheet 20 of Figs. 1 and 2, extending to the end of this panel as viewed in Fig. 6. As shown particularly in Fig. 5, however, a panel of this type may be provided with its marginal portions bent outwardly and then curved to afford a substantially semi-cylindrical bead 30, then continued inwardly to afford a reinforcing portion 31 in a plane substantially normal to that of the body portion and finally being continued inwardly to afford a flange 33 similar to the flange 3 and similarly adapted to cooperate with the body portion in affording a channel to receive the end of an index strip. Fig. 4 shows the arrangement of the ears 15^a upon this type of frame, these ears receiving the looped or flattened tubular extremity of the cover sheet 20^a in the manner already described with reference to the frame 10 and cover sheet 20 and, if desired, containing a reinforcing strip 17^a.

The beading 30 not only affords a substantial reinforcement for the frame, but permits it to have adequate strength while allowing the flanges 33 to be relatively narrow so that less difficulty is faced in locating the extremities of the index strips in the marginal channels. The beads thus provided at the edges of the panel also extend outwardly beyond the edges of the transparent covering sheet 20^a thus affording protection for the edge of the sheet and avoiding the possibility of catching the same upon a foreign object.

It is evident that this invention affords an index frame or panel adapted to be received in a larger frame, such as a frame of the book type and provided with a readily detachable continuous covering sheet of transparent material particularly effective to protect the individual index elements or strips. Furthermore, this invention affords an arrangement of the marginal portion of a panel which not only is effective in reinforcing the latter and affording adequate strength while permitting relatively narrow marginal flanges or channels, but also is effective in protecting the edges of the transparent covering or protective sheet.

I claim:

1. An index frame comprising a body portion of sheet metal, opposite inturned retaining flanges having ends spaced from the upper and lower edges of the body portion, and inturned ears substantially in the planes of but separate from the flanges, said ears being disposed between the ends of the flanges and the upper and lower edges of the body portion, index material held in place by the retaining flanges, and a flexible transparent cover sheet for said index material, said cover sheet having end portions in-turned and hooked over said ears, each end of the cover sheet being distortable so that it may be bent away from the end of the body portion to permit disengagement of that end of the sheet from the corresponding ears.

2. Index arrangement comprising a frame having a body portion of sheet material and opposite inturned retaining flanges, said flanges terminating in spaced relation to the upper and lower edges of the body portion, the body portion being extended to provide inturned ears adjoining each extremity of each flange, said retaining flanges cooperating with the body portion to afford channels to receive index strips, and a detachable transparent cover sheet formed of resilient material and having flattened end loops receiving the ears in interfitting engagement therewith, said loops and the adjoining portions

of the sheet being distortable to permit disengagement of the loops from the ears.

3. Index arrangement comprising a frame having a body portion of sheet material and opposite inturned retaining flanges, said flanges terminating in spaced relation to the upper and lower edges of the body portion, the body portion being extended to provide inturned ears adjoining each extremity of each flange, said retaining flanges cooperating with the body portion and affording channels to receive index strips, a detachable transparent cover sheet formed of resilient material and having flattened end loops receiving the ears in interfitting engagement therewith, said loops and the adjoining portions of the sheet being distortable to permit disengagement of the loops from the ears, and stiffening strips of distortable sheet material within the loops and normally extending between the ears.

4. An index frame assembly comprising a master frame having parallel retaining flanges, a smaller frame having parallel retaining flanges extending at right angles to the retaining flanges of the master frame and having end flanges underlying the retaining flanges of the master frame, a retaining strip normally extending between corresponding ends of the retaining flanges of the master frame but being movable relative to the master frame to permit removal of the smaller frame, whereby the smaller frame may be moved in one direction along the flanges of the master frame and removed from the latter, and retaining means at the opposite ends of the flanges of the master frame to prevent removal of the smaller frame by movement along the flanges of the master frame toward said means.

5. An index frame assembly comprising a master frame having parallel retaining flanges, a smaller frame having parallel retaining flanges extending at right angles to the retaining flanges of the master frame and having end flanges underlying the retaining flanges of the master frame, and a retaining strip normally extending across the ends of the retaining flanges of the master frame but being removable relative to the master frame to permit removal of the smaller frame, the smaller frame being provided with a transparent covering sheet terminating inwardly of said end flanges and covering the area between the retaining flanges of the smaller frame.

6. An index frame comprising a body portion of sheet metal having flanges at its opposite edges provided by extending the metal outwardly and bending the same to afford a return bent portion at each of said edges of the body portion, then by extending the metal inwardly substantially parallel to the body portion thereof to afford a retaining flange at each of said edges of the frame, each retaining flange terminating in spaced relation to the end of the corresponding return bent portion and the metal being extended inwardly from the end of said return bent portion to afford an ear spaced from but substantially coplanar with the adjoining retaining flange whereby two opposed ears are provided at the end of the frame to receive a retaining or covering element.

7. Index frame assembly comprising a master frame having opposite coplanar retaining flanges, ears disposed at the corresponding ends of the flanges, a tubular element of distortable material having its ends engaging said ears, retaining means extending between the opposite ends

of the flanges, a smaller frame having end flanges disposed beneath the retaining flanges of the master frame and being held against removal by said tubular element and by said retaining means, the smaller frame having retaining flanges extending at right angles to the flanges of the master frame.

5. An index frame comprising a body portion of sheet metal provided with opposite inturned retaining flanges, said flanges having their ends spaced from one end of the body portion, the body portion being provided with ears adjoining and substantially in alignment with the ends of the retaining flanges and a cover sheet of 10
15 distortable transparent material having an end portion inturned and disposed beneath said ears, the opposite end of said cover sheet being detachably secured to the opposite end of the frame.
20. 9. An index frame comprising a body portion of sheet metal provided with opposite inturned retaining flanges, said flanges having their ends spaced from one end of the body portion, the body portion being provided with ears adjoining

and substantially in alignment with the ends of the retaining flanges and a cover sheet having an end portion folded to afford a flattened distortable tubular element with the ears received in interfitting relation with the ends of the element, whereby the intermediate part of the flattened element may be bowed outwardly to permit disengagement of its ends from said ears, the opposite end of the cover sheet having an inturned extremity extending beneath a portion 10
15 of the frame.

10. An index frame having a sheet metal body portion and having opposite ears at its margins formed by turning extensions of the body portion back substantially parallel thereto, and a flattened tubular element of sheet material having a continuous outer surface with end portions overlying said ears, and having an underlying inner surface with end portions underlying the ears, said tubular element being distortable so 20
25 that its mid portion may be bowed away from said body portion to permit removal of the element from the ears.
